UNITED STATES PATENT OFFICE.

EDWIN O. KLEMM, OF SAGINAW, MICHIGAN.

AUTOMATIC BRAKE FOR SOUND-REPRODUCING MACHINES.

1,089,230.

Specification of Letters Patent.

Patented Mar. 3, 1914.

Application filed June 24, 1912. Serial No. 705,464.

To all whom it may concern:

Be it known that I, EDWIN O. KLEMM, a citizen of the United States, residing at Saginaw, in the county of Saginaw and 5 State of Michigan, have invented certain new and useful Improvements in Automatic Brakes for Sound-Reproducing Machines, of which the following is a specification.

The present invention relates to improvements in automatic brakes for sound reproducing machines designed particularly for use in connection with such machines of the disk type.

The object in view is to provide brake mechanism capable of automatically stopping the rotation of the turn-table upon which the record is carried immediately upon completion of the record being reproduced.

Still a further object of my device is the provision in association with the braking mechanism of means for adjusting the same to operate the brake at a predetermined time controlled primarily by the length of 25 the groove of the record or the point at which the sound to be reproduced ceases.

For a full understanding of the present invention, reference is to be had to the following description and the accompanying 30 drawings, in which—

Figure 1 is a top plan view of a machine equipped with my invention, parts being broken away to show more clearly the details of construction; Fig. 2 is a side elevation; Fig. 3 is a fragmentary view showing a modified form of brake lever for operation against the outer flanged periphery of the turn-table; Fig. 4 is a fragmentary sectional view taken about on the line 4—4 of 40 Fig. 1; and Fig. 5 is a detail view showing the adjusting cam provided with a lever.

Throughout the following detail description and on the several figures of the drawings, similar parts are referred to by like 45 reference characters.

Referring to the drawings and specifically describing the invention, A designates the casing of a sound producing machine, in which is contained a motor for revolving 50 the turn-table B, said casing having revolvably mounted thereupon the reproducer arm C which in turn carries the sound box D and stylus E, all of conventional form.

The brake mechanism constituting my invention is mounted substantially beneath the turn-table B and consists of a base or ad-

justing plate 1 preferably of somewhat triangular shape, pivotally mounted at its reduced or tapered portion upon the spindle 2 which carries the turn-table aforesaid, said plate resting upon the top of the casing A. The plate 1 is provided with a stud 3 on its upper surface which forms the pivot of a controlling lever 4. The controlling lever 4 is formed at one side with a 50 projecting arm 5 which extends beyond the turn-table B and is bent upwardly, the length of said arm being such that it will lie in the path of the reproducer arm C. Also pivotally mounted intermediate its 55 length upon stud 3 is the brake lever 6, one end of which is bent upwardly adjacent the inner flanged periphery of the turn-table B, the bent portion designated 6' constituting a brake shoe which is provided with the 60 leather or other suitably covered face. The opposite end portion of the lever 6 extends toward the central portion of the machine, and has connected thereto one end of a spring 7, the other end of the latter being 65 suitably secured to the adjusting plate 1.

Near the outer edge portion of the plate 1 is pivotally mounted a pawl 8, the free hooked end of which is adapted to engage 70 with a lug 9 which is suitably fastened or 75 formed on the surface of the brake lever 6. On one edge of the controlling lever are 80 formed upwardly projecting spaced guide lugs 10 between which the pawl 8 lies, as 85 clearly shown in Fig. 1.

With the foregoing in view, it is to be understood that the brake mechanism as shown in Fig. 1 is in a position ready to be tripped, assuming that the turn-table B with the record disk 11 thereon is in motion. As 90 the stylus E approaches the inner terminal of the spiral groove in the record, the reproducer arm C, at a predetermined time to be more fully hereinafter described, will contact with the controlling lever or rather its arm 5, which moving on its pivot, causes the guide lugs 10 to disengage the pawl 8 from the lug 9. The tension of the spring 7 immediately pulls the lever 6 around on its pivot, and forces the shoe 6' to impinge 95 against the flanged periphery of the turn-table B, stopping the rotation of the latter in an obvious way.

As sound reproducing records vary considerably in length, it is desirable to provide means for actuating the brake mechanism above described at a predetermined 100

time, and to this end I form the face or adjusting plate 1 with a forked extension 12 which is bent upwardly beyond the edge portion of the turn-table and back again parallel with the top of the casing A as shown most clearly in Fig. 2. Suitably mounted upon the top of the casing A in a socket 13 is an eccentric cam 14, the edge portion of which is grooved to receive the forked extension 12, which thus becomes a cam follower. The cam 14 is provided with means for turning the same, such as a knob 15 or a hand lever, designated 15^a in Fig. 5. The record disk 11 having previously been tested as to point of cessation of the sound to be reproduced, is preferably marked in any desirable manner such as shown in Fig. 1 by placing a pasteur bearing a numeral, which in this instance is 4. When the record is to be reproduced, the operator moves the cam 14 by means of the knob 15 to a position corresponding to the numeral 4 on the disk above mentioned, this position being determined by an arrow on the cam 14, which is turned to the corresponding numeral 4 which is marked upon a forked extension 12. The movement of the cam 14 will obviously move the plate 1 backward or forward so as to bring the arm 5 of the controlling lever into contact with the reproducer arm at a sooner or later time. Thus, if the record be a short one, the designated numeral on the record will indicate to the operator that the arm is to be moved forwardly to contact with the reproducer arm C at the corresponding point as indicated by the numeral on the forked extension 12. Accordingly, if the record be longer, the arm 5 is moved backwardly away from the reproducer arm a farther distance.

The advantages of my device as above described, will be apparent to those skilled in the art to which it refers. The operator needs only to place the record upon the turn-table with the preliminary adjustment hereinbefore described, and the record may then be reproduced without further attention on the part of the operator when it has been completed.

Various changes may be made in the details of construction of my device without departing from the spirit of the invention, and within the scope of the claims hereto appended.

It may be desirable that the brake shoe operate against the outer flanged periphery of the turn-table, and in Fig. 3, I have shown the lever 6^a formed with a shoe 6^b which projects beyond the outer circumference of the turn-table B for frictional contact therewith.

In setting the brake mechanism when the record has been placed upon the turn-table, the operator moves the arm 5 forwardly, thereby bringing a stud 4' carried by the sur-

face of the controlling lever 4 into contact with the edge of the brake lever 6 mounted thereupon. The lever 6 is thus moved until the pawl 8 is caused by the guide lugs 10 to engage around the lug 9 on the brake lever 6, placing said lever under the tension of the spring 7. In Fig. 3, the modified form of brake lever 6^a is provided with a notch in which the stud 4' on the controlling lever 4 operates as above described. 75

It is preferable for purpose of convenience that the pasteur, carried by the record and which indicates the point of tripping of the brake, should have associated therewith a letter to denote the style of needle to be used with that record to produce best results, for example, F indicating fiber needle, M for musical, H for half tones, etc. 80

Having thus described the invention, what is claimed as new is:

1. An automatic brake for sound reproducing machines comprising, in combination, a rotating element and a moving element, a brake lever, a spring connected with one end of the brake lever and normally holding the same under tension, a brake shoe on the opposite end of the lever, a lug carried by the brake lever, a pawl having its free end adapted to engage with the lug aforesaid to hold the brake shoe from contact with the rotating element, a controlling lever coöperating with the brake lever and having an arm lying in the path of movement of the moving element aforesaid, and spaced guide lugs carried by the controlling lever between which the pawl aforesaid rests, whereby the pawl may be disengaged from the lug on the brake lever by contact of the moving element with the arm of the controlling lever. 95 100 105

2. An automatic brake for sound reproducing machines comprising, in combination, a rotating element and a moving element, a brake lever adapted to coöperate with the rotating element, a controlling lever adapted to release the brake lever to permit operation of the same, variable adjusting means upon which the brake and controlling levers are mounted, and means for moving the last mentioned adjusting means to adjust the position of the controlling lever aforesaid for operation of the brake at variable times. 110 115

3. An automatic brake for sound reproducing machines comprising, in combination, a rotating element and a moving element, a brake lever adapted to coöperate with the rotating element, a controlling lever adapted to operate the brake lever, an adjusting plate upon which the brake and controlling levers are mounted having an extension formed thereon, and means carried by the machine coöperating with the extension of the adjusting plate for moving the latter in a path parallel with the path of travel of 120 125 130

the periphery of the rotating element to adjust the position of the controlling lever.

4. An automatic brake for sound reproducing machines comprising, in combination, 5 a rotating element and a moving element, an adjusting plate, a controlling lever associated with the plate and adapted to engage with the moving element, a spring actuated brake lever normally held disengaged from 10 the rotating element, and an indicator movable to adjust the plate aforesaid and thereby adjust the position of the controlling lever for operation of the brake lever at a predetermined time.

- 15 5. An automatic brake for sound reproducing machines comprising, in combination, a rotating element and a moving element, an adjusting plate, a controlling lever associated with the plate and adapted to 20 coöperate with the moving element, a spring actuated brake lever normally held disengaged from the rotating element, and an eccentric cam coöperating with the adjusting plate and movable to adjust the controlling 25 lever for operation of the brake lever at a predetermined time.

6. An automatic brake for sound reproducing machines comprising, in combination, a rotating element and a moving element, 30 an adjusting plate pivotally mounted beneath the rotating element and having a forked extension projecting beyond the latter, a controlling lever pivotally mounted upon the plate aforesaid, an arm carried by 35 said lever and in the path of movement of the moving element, a spring actuated brake lever pivotally mounted upon the plate and coöperating with the controlling lever, a pawl carried by the plate and adapted to 40 engage with the brake lever to hold the same from contact with the rotating element, and an eccentric cam comprising an indicator coöperating with the forked extension of the adjusting plate, whereby the arm of the 45 controlling lever may be adjusted to operate the brake lever.

7. An automatic brake for sound reproducing machines comprising, in combination, a rotating element and a moving element, 50 an adjusting plate pivotally mounted beneath the rotating element and having a forked extension projecting beyond the same, a controlling lever pivotally mounted upon said plate and having spaced vertical 55 guide lugs formed thereon, an arm carried by the controlling lever and bent upwardly

into the path of movement of the moving element, said controlling lever having a stud thereon, a spring actuated brake lever pivotally mounted upon the controlling lever 60 and having a brake shoe adapted to contact with the rotating element, a lug carried by the brake lever, a pawl pivotally mounted on the adjusting plate aforesaid and engageable with the lug on the brake lever to 65 hold the brake shoe from contact with the rotating element, said pawl coöperating with the spaced guide lugs on the controlling lever and adapted to be engaged with the lug on the brake lever when the latter 70 is moved by the lug on the controlling lever, and an eccentric cam pivotally mounted upon the casing aforesaid and having a grooved periphery to receive the forked extension of the adjusting plate, said extension and cam comprising indicating means whereby upon movement of the cam into a predetermined position, the arm of the controlling lever may be adjusted to coöperate 75 with the moving element. 80

8. An automatic brake for sound reproducing machines comprising, in combination, a swinging arm, a rotating support, a spindle for said support, a plate connected with the spindle aforesaid, a controlling lever carried by the plate, a brake lever coöperating with the controlling lever, and means for moving the plate a predetermined extent about the spindle as an axis to adjust the controlling lever for operating the brake 90 lever at a predetermined time. 85

9. An automatic brake for sound reproducing machines comprising, in combination, a swinging arm, a rotating support, a brake lever adapted to engage the support, a controlling lever adapted to coöperate with the arm, a pivot common to both the brake and controlling levers, means for holding the brake lever in an inoperative position, means intermediate the arm and last mentioned 100 means adapted to release the brake lever, and a plate adapted to be moved to adjust the controlling lever aforesaid for operation of the brake lever at a predetermined time, said plate carrying the pivot for the brake 105 and controlling levers. 95

In testimony whereof I affix my signature in presence of two witnesses.

EDWIN O. KLEMM.
